UNITED STATES PATENT OFFICE.

OTTO JOHN BOETTCHER, OF CHILTON, WISCONSIN, ASSIGNOR OF TWO-FIFTHS TO FRED W. MAAS AND ONE-FIFTH TO GEO. C. HUME, BOTH OF CHILTON, WISCONSIN.

HOISTING TACKLE.

1,422,174.

Specification of Letters Patent. Patented July 11, 1922.

Application filed December 9, 1921. Serial No. 521,180.

To all whom it may concern:

Be it known that I, OTTO J. BOETTCHER, a citizen of the United States, residing at Chilton, in the county of Calumet and State 5 of Wisconsin, have invented certain new and useful Improvements in Hoisting Tackle, of which the following is a specification.

This invention relates to hoisting tackle in which pulley blocks are used to obtain the 10 necessary power; and it consists in the novel construction and combination of the parts hereinafter fully described and claimed which enable flat straps or bands to be used in place of the ropes or chains ordinarily 15 used.

In the drawings, Figure 1 is a side view of a hoisting tackle constructed according to this invention. Fig. 2 is a view showing the devices turned around one-quarter from the 20 position shown in Fig. 1. Fig. 3 is a detail side view of the automatic catch. Fig. 4 is a front view of the same.

The upper block 6 has two parallel side plates 7, and a suspension hook 8. A flat 25 leather strap 9 is used in place of the usual rope or chain, and flat bands of other flexible material may also be used. One end of the strap 9 is secured to a crossbar 10, on the upper block, and a roller 12 is journaled 30 on a pin 14 in the upper block for the strap to pass over.

The lower block 15 has side plates 16, and a roller 17 is journaled on a pin 18 between the side plates, for the strap to pass under. 35 The block 15 has a lifting hook 19 pivoted on a pin 20 at its lower part, and this hook is preferably a snap hook.

A catch roller 21 of larger diameter than the roller 17, so that the stretches of the 40 strap will not run against each other, is journaled on a pin 22, and is arranged between the roller 17 and the lifting hook, and an automatic catch 24 is pivoted on the pin 20. This catch 24 is a cam provided with 45 a serrated outer surface, and it is pivoted to the pin by a double-eye 25 which straddles the eye of the lifting hook.

The strap 9 passes downwardly from the cross bar 10 under the roller 17, thence up and over the roller 12, and downwardly between the catch roller 21 and the catch 24. 50

When the fall 26 is held in the position shown, parallel to the pull of the load, and is slackened, the cam-shaped catch is turned on its pivot pin by contact with the strap, 55 so that the strap is gripped between the catch and the catch roller.

This tackle is specially adapted for use by linemen in making repairs on telephone and other electric lines, and is used to pull up 60 the wires. The automatic catch enables the lineman to hold the wire under any desired tension in making repairs.

The strap is released by first pulling the fall 26 a little downwardly, when the tackle 65 is in the position shown in Fig. 1, so as to turn the catch on its pivot; and then bending the fall upwardly around the periphery of the roller 21, without letting the strap slide backwardly, until the fall is clear of 70 the catch.

What I claim is:

A tackle, comprising a block having a flat-faced roller journaled in it, a second block having two flat-faced rollers arranged 75 tandem and journaled in it, a cam-shaped sustaining catch provided with a double-eye which is pivoted in the second block in line with its two rollers, a lifting member pivoted between the two eyes of the said double-eye, said catch and lifting member being mounted on the same pivot and being independently movable, and a flat operating strap which engages with the said catch and passes over the said rollers and is secured 80 at one end to the first said block, said catch operating to clamp the strap against one of the rollers of the said second block. 85

In testimony whereof I have affixed my signature.

OTTO JOHN BOETTCHER.
